SPINNING REEL

Michael J. Koenecke, Estherville, Iowa, and Richard J. Hughes, Des Plaines, Ill., assignors to Berkley & Company, Inc., Spirit Lake, Iowa

Continuation-in-part of design application Ser. No. 232,332, Mar. 6, 1972. This application Oct. 4, 1972, Ser. No. 295,015

Term of patent 14 years

Int. Cl. D22—05

U.S. Cl. D22—25

FIG. 1

FIG. 2

FIG. 3

FIG. 6

FIG. 4

FIG. 5

FIG. 7

FIG. 8

FIG. 9

FIG. 1 is a front perspective view of a spinning reel;
 FIG. 2 is a front perspective view of the other side;
 FIG. 3 is a rear perspective view;
 FIGS. 4 and 5 are front and rear views respectively;
 FIG. 6 is a view similar to FIG. 3, showing a second embodiment wherein the attaching handle differs;

FIGS. 7, 8 and 9 are side, top, and bottom views respectively of a third embodiment wherein the attaching handle, mode selection lever, and brake switch differ.

This is a continuation-in-part of application 232,332, filed Mar. 6, 1972.

We claim:
 The ornamental design for a spinning reel, as shown and described.
